UNITED STATES PATENT OFFICE.

ADAM H. PRENZEL, OF HALIFAX, PENNSYLVANIA, ASSIGNOR TO UNITED SHOE MACHINERY COMPANY, OF PATERSON, NEW JERSEY, A CORPORATION OF NEW JERSEY.

PROCESS OF MAKING SHOES.

1,117,088.

Specification of Letters Patent. Patented Nov. 10, 1914.

Application filed October 12, 1912. Serial No. 725,478.

To all whom it may concern:

Be it known that I, ADAM H. PRENZEL, a citizen of the United States, residing at Halifax, in the county of Dauphin and 5 State of Pennsylvania, have invented certain Improvements in Processes of Making Shoes, of which the following description, in connection with the accompanying drawings, is a specification, like characters on the 10 drawings indicating like parts in the several figures.

This invention relates to processes of making shoes and is particularly applicable to the manufacture of shoes in which the 15 sole is attached to an outturned flange of the upper. These shoes, commonly termed "stitch-downs," are of two general classes,— those in which a continuous flange is formed upon the upper and stitched down upon the 20 sole all the way around, and those in which a portion of the upper is lasted in over an insole or over a heel seat piece while the remaining portion is turned out and stitched down in the usual manner.

25 A common objection to the first type of stitch-down shoe is the appearance of the heel end of this shoe. In order to provide for turning out the upper and stitching it down upon the sole at the heel end of this 30 type of shoe, the heel must be considerably larger than the ordinary heel upon a shoe of the same size and must necessarily, therefore, be considerably heavier. In making the second type of stitch-down shoe difficulty 35 has been experienced in making a neat joint where the outturned and inturned portions of the upper meet and, when the upper has been lasted in only at the heel seat, difficulty has also been experienced in conforming the upper to the last in the region of the 40 shank. This latter difficulty has been experienced up to the present time in making all types of stitch-down shoes.

An object of the present invention is to 45 produce a stitch-down shoe which in every way will present as neat an appearance as a shoe of any other type.

To this end the invention aims to produce a stitch-down shoe in which the upper shall 50 be lasted in only at the heel seat and shall be turned out and stitched down upon the sole through the shank and about the forepart, which shall have a tight and neat appearing joint where the outturned and in- 55 turned portions of the upper meet, which

shall be properly conformed to the last in the shank and shall be so constructed as to keep its original neat appearance after long wear, and which can be manufactured with a minimum of labor and expense.

Other objects and novel features of the invention will appear from the following description and claims when considered in connection with the accompanying drawings, in which,—

Figure 1 is a perspective view showing the novel last and the novel insole employed in carrying out the process of this invention; Fig. 2 illustrates the outsole employed when the shoe is either a no-heel shoe or a 25 shoe having an outside heel built up of lifts; Fig. 3 shows the formation of the outsole for a spring heel shoe; Fig. 4 shows the arrangement of the upper and lining and the contour of the lining at the toe end of the 75 shoe; Fig. 5 illustrates the shoe after the lining has been turned in and cemented down upon the insole and after the heel end of the upper and counter have been turned in and lasted down upon the insole; Fig. 6 is a detail perspective, partly in section, showing the mode of lasting the upper through the shank and forepart region and the location of the welt abutting lift with respect to the outturned portion of the upper; Fig. 7 is a detail section showing the relative locations of the different parts of the completed shoe while it is still upon the last; Fig. 8 is a side elevation of a completed shoe.

An important feature of the invention is the forcing of the angle of the upper beneath the edge of the insole during the lasting operation whereby the inner edge of the welt may also be brought beneath the edge 95 of the insole or in the crease of the upper, thereby improving the appearance of the shoe and providing a firm support for the upper upon the inside of the shoe so that it does not draw back from the welt, as in the 100 ordinary stitch-down shoe. To facilitate obtaining this result from the lasting operation, the last 2 employed in this process is preferably beveled along the bottom edge, as shown at 4, in Figs. 1 and 7, and a bevel 105 6 is preferably also provided upon the insole 5. It will be understood, however, that in some cases one of these bevels may be dispensed with, particularly when the insole is comparatively thin. The outer edge of the 110

insole, when it has been placed upon the last, is preferably substantially flush with the side of the last and the insole is temporarily secured upon the last in this position by any suitable fastening means, such as stay tacks 8 shown in Fig. 1.

After the insole has been placed upon the last, an upper 10 having a lining 12 is placed upon the last, the lining 12 of the upper preferably projecting beyond the edge of the upper in order to provide for a considerable margin to be turned in and cemented down upon the insole. About the toe end the lining is preferably notched, as shown at 14, so that when it is turned in over the edge of the insole it may be cemented down smoothly upon the insole, as shown in Fig. 5. The upper and insole having been placed upon the last, the lining is drawn tight over the edge of the insole and cemented down upon the insole all the way around. A convenient mode of effecting this cementing operation is to prepare a number of insoles by spreading glue over the bottom face, preferably over the whole of the bottom face, and then allowing the glue to dry upon the insoles until they are ready for use. When the operation of lasting in the lining over the insole is to be performed, the insole may then be passed over a jet of steam to soften up the glue, after which the cementing operation can easily be performed by simply pressing the lining into the glue upon the bottom face of the insole. The lining having been turned in and cemented down upon the bottom face of the insole, the heel end 15 of the upper and the counter 16 are turned in and lasted down upon the insole, preferably by means of lasting tacks in the usual manner. After the heel seat has been lasted in, an outsole 17 is placed on the last and the lower margin of the forepart and shank of the upper is then turned out and lasted down upon this outsole. In order to permit the upper to be turned in at the heel end and lasted down upon the insole and turned out in front of the heel and lasted down upon the outsole, the upper is preferably cut in from the edge upon each side, as shown at 18 and 20, to the line where the flange is to be turned out.

From an inspection of Fig. 6 it will be noted that the outturned flange of the upper will form a thickness upon the upper face of the sole margin which will not extend around the heel end of the sole. Moreover when the welt has been laid upon this outturned flange and the parts have been united by stitches in the usual manner, another thickness of material will appear upon the sole margin through the shank and about the forepart which will not appear upon the heel end of the sole. The thickness of the edge of the sole will, therefore,

appear to be much greater through the shank and about the forepart than at the heel end. Moreover the appearance of the joint where the inturned and outturned portions of the upper meet will be very unsatisfactory because of the abrupt termination of the welt at this point. To improve the appearance of the joint at this point, and at the same time to provide a better joint at this point, the outsole is preferably provided upon the upper face of its heel end with a raised welt abutting portion which may be in the form of a lift 22 of such a thickness upon its outer edge that the exposed upper face of this lift will lie substantially flush with the upper face of the welt. In Fig. 2 is shown an outsole provided with such a lift upon the upper face of its heel end, this outsole being adapted especially for use either with a shoe having no heel or with a shoe having a heel built up on the outside or bottom face of the outsole.

When the invention is to be practised in the manufacture of spring heel shoes, the outsole is preferably built up, as shown in Fig. 3, the underwedge or spring lift 24 being inserted between the welt abutting lift 22 and the upper face of the heel end of the sole, and the sole being then pressed down or sprung, as shown at 26, so that the front edge of the outer margin of the welt abutting lift 22 will project above the shank portion of the sole sufficiently to cause the exposed edge of this lift to lie substantially flush with the upper face of the welt in the finished shoe.

In preparing the outsole for the lasting step, the welt abutting lift 22 is preferably cemented upon the upper face of the heel end of the outsole and is then pressed firmly in position, the center of this lift being preferably depressed, as shown in Fig. 2, to bring its upper surface near the upper surface of the remaining portion of the outsole. The outsole is preferably also prepared for the lasting operation in a manner similar to the preparation of the insole hereinabove described, that is, the outsole is preferably provided over its whole upper face with a coating of glue which is allowed to dry upon the outsole until the outsole is ready for use. When the outsole is to be used, its coating of glue is exposed to a jet of steam and softened and the outsole is then located carefully upon the last with the forward edge of the welt abutting lift 22 abutting against the rear edges of the outturned flange 30 of the upper, the outsole being pressed down so that it adheres to the insole and to the inturned lining. The lower margin of the upper along the shank and about the forepart is then turned out and the upper is drawn tightly over the last and secured in lasted position, preferably by staples 32 inserted in the angle of the up-

per close to the side of the last. This lasting operation may conveniently be performed upon a machine of the type disclosed in my co-pending application Serial No. 725,477 filed Oct. 12, 1912.

Inasmuch as the edge of the last has been beveled, as shown at 4, and, in the illustrated shoe, the edge of the insole has also been beveled, as shown at 6, during this 10 lasting operation the angle of the upper may be forced in between the edge of the insole and the outsole, thus forming a deep crease in the upper into which the inner edge of the beveled welt 34 may be thrust, thereby forming a tight joint between the 15 welt and the upper and also insuring proper support for the upper upon the inside of the shoe.

It will be noted from an inspection of Fig. 7 that the staples 30 are driven into the angle 31 of the upper at such an inclination to the face of the sole that the legs of the staples extend beneath the edge of the last and beneath the edge of the insole. The 20 staples are thus inserted in directions substantially transverse to the direction of pull of the stretched upper and in such directions that when the heads of the staples are covered by the welt, as shown in Fig. 7, there is substantially no opportunity for 25 the staples to work loose. The insole being cemented firmly down upon the outsole within the bounds of its beveled edge, a shoe is produced in which the upper is firmly 30 supported in its lasted condition and which will keep its shape after the last is removed and even after long wear. As suggested above, the welt 34 is preferably beveled so that it is thinner upon its inner edge than 35 upon its outer edge. An important reason for beveling this welt, in addition to that of permitting it to be thrust easily beneath the overhanging part of the upper into the crease or angle 31 formed between the upper and the outturned flange, is the desirability of covering the outer edge 36 of this flange in order that it may not be exposed to interfere with the finishing operation upon the edge of the sole. After the lasting 40 operation, this edge of the upper is preferably trimmed back from the edge of the sole, as shown in Fig. 6, so that when the beveled welt 34 is placed upon the edge the thicker outer edge of this welt will overhang the edge of the upper flange and the 45 lower face of the welt will contact with the upper face of the sole margin, thus making a tight joint along the edge of the sole for the finishing operation. When the welt is placed upon the upper margin 39, one end of the welt is carefully abutted against the exposed portion of the front edge of the 50 welt abutting lift 28 upon the heel of the shoe and the other end is abutted against the toe portion of the front edge of the upper 55 margin 39. The finishing operation 55

against the other exposed portion of the front edge of said lift 22. The stitches 38 are preferably inserted close to the side of the upper so that they will pass through the welt, upper flange and sole and so that they will also insure maintenance of the upper in shape after the last has been removed. After the welt, the outturned flange of the upper and the outsole have been stitched together and the ends of the welt have been abutted against the exposed portions of the front edge of the lift 22, the heel end of the sole is attached to the insole, upper and counter, preferably by nails driven through these parts and clenched upon the inside of the shoe in the usual manner. These nails are preferably so located that the edge of the heel end of the sole and the edge of the lift 22 may be trimmed close to the side of the upper in the manner usual in the making of the better grades of shoes. If an outside heel is employed, such as shown in Fig. 8, the nails are preferably inserted through this heel also. When nailing the parts together, care is taken to have the parts securely nailed near the junction of the outturned and inturned parts of the upper so that a tight joint may be secured at this point.

In Fig. 8 of the drawings is shown in side elevation a finished shoe. From this figure it will be noted that the exposed sole edge has an appearance of uniform thickness all the way around, that the heel seat end of the sole does not differ in appearance from the heel seat end of any of the better grades of shoes, such for example as the Goodyear shoe, and that the creasing under of the upper about the forepart and particularly about the toe serves further to improve the appearance of the shoe and to produce a shoe which can scarcely be distinguished from a Goodyear shoe. Not only is the appearance of the shoe substantially that of the better grades of shoes, but from the foregoing description of the process of making this shoe and of its construction it will be apparent that both the fit and wearing qualities of the shoe are substantially equal to those of the better grades of shoes.

It will be noted from an inspection of Figs. 4 and 5 that the shoe illustrated in the drawings comprises, besides the upper 10 and the lining 12 a toe cap 46 and a strip of stiffening material 42. As shown in the drawings, these parts are lasted into their final shape together with other parts of the shoe. It will be understood, however, that the invention can be practised to equal advantage, and possibly in some cases to better advantage, if the toe part of the upper together with the toe stiffener and toe cap are molded into substantially their final shape before the upper is placed upon the last. The invention contemplates

also molding the counter and the heel end of the upper into substantially their final shapes before the lasting operation upon these parts.

5 It will be understood that some of the novel steps of the invention may be practised without the use of all of the parts herein shown; for example, a complete insole is not necessary in order to obtain many of
10 the advantages of the invention.

That improvement in the art of making shoes which consists in assembling upon a last an upper and a sole which has a margin projecting beyond the bottom edge of
15 the last and then uniting the upper to the sole by staples driven through the upper into the sole in close proximity to said bottom edge of the last with the bodies of the staples parallel to said edge has been made
20 the subject-matter of my co-pending application Serial No. 725,476 filed Oct. 12, 1912, and all claims to this subject-matter which are broad enough to read upon the disclosure in the present application as well as upon
25 the disclosure in said co-pending application will be made in said co-pending application.

The novel shoe produced by the process hereinabove described is not herein claimed
30 but is made the subject matter of my co-pending application, Serial No. 863,129, filed September 23, 1914, the said co-pending application being a division of this application.

35 Having described my invention, what I claim as new and desire to secure by Letters Patent of the United States is:—

1. That improvement in the art of making shoes which consists in assembling upon a
40 last an upper and an insole, applying an outsole and providing a space between the edge of the insole and the outsole, turning out the lower margin of the upper, progressively shaping the upper to the last and
45 forcing the angle of the upper into said space between the edge of the insole and the outsole, permanently securing the upper to the outsole in said angle as the shaping progresses, laying a welt upon the outturned margin of the upper, and uniting the welt, upper and outsole.

50 2. That improvement in the art of making shoes which consists in assembling upon a last an upper and an insole which has its edge substantially flush with the edge of the last, securing to the bottom face of said insole an outsole which has a margin projecting beyond the bottom edge of the last and providing a space between the edge of said
55 insole and said outsole, turning out the lower margin of the upper, progressively shaping the upper to the last and forcing the angle of the upper into the space between the insole and the outsole, permanently securing the upper to the outsole in
60 said angle with the bodies of the staples parallel to the bottom edge of the last and the legs inclined to the face of the outsole, trimming the upper margin back from the edge of the sole, laying upon said upper margin a welt which is thicker at its outer edge.

65 said angle as the shaping progresses, laying a welt upon the outturned margin of the upper, and uniting the welt, upper and outsole.

3. That improvement in the art of making
70 shoes which consists in assembling upon a last an upper and an insole which has its edge substantially flush with the edge of the last, securing to the bottom face of said insole an outsole which has a margin projecting beyond the bottom edge of the last and providing a space between the edge of
75 said insole and said outsole, turning out the lower margin of the upper, progressively shaping the upper to the last and forcing the angle of the upper into the space between the insole and the outsole, permanently securing said upper to the outsole, as the shaping progresses, by staples inserted in said angle with the bodies of the
80 staples parallel to the bottom edge of the last, laying a welt upon the outturned upper margin, and uniting the welt, upper and outsole.

4. That improvement in the art of making
85 shoes which consists in assembling upon a last an upper and lining and an insole which has its edge substantially flush with the edge of the last, turning in the lining and securing it to the bottom face of the
90 insole, applying an outsole which has a margin projecting beyond the bottom edge of the last and providing a space between the edge of the insole and the outsole, turning out the lower margin of the upper, progressively shaping the upper to the last and forcing the angle of the upper into the space between the insole and outsole, permanently securing the upper to the outsole in said angle as the shaping progresses, laying a welt upon the outturned margin of the upper, and uniting the welt, upper and outsole.

95 5. That improvement in the art of making
100 shoes which consists in assembling upon a last an upper and lining and an insole which has its edge substantially flush with the edge of the last, turning the lining in and securing it to the bottom face of the insole, applying an outsole which has a margin projecting beyond the bottom edge of the last and providing a space between the edge of the insole and the outsole, turning out the lower margin of the upper, progressively shaping the upper to the last and forcing the angle of the upper into the space between the insole and the outsole, permanently securing the upper to the outsole, as the shaping progresses, by staples inserted in said angle with the bodies of the staples parallel to the bottom edge of the last and the legs inclined to the face of the outsole, trimming the upper margin back from the edge of the sole, laying upon said upper margin a welt which is thicker at its outer edge.

105 110 115 120 125 130

120 125 130

then at its inner edge whereby its outer edge overhangs the edge of the upper and its inner edge enters the angle of the upper and covers the heads of the staples, and uniting the welt, upper and outsole.

6. That improvement in the art of making shoes which consists in assembling upon a last an insole, an upper and a lining which projects beyond the bottom edge of the upper, turning the lining in and securing it to the bottom of the insole, applying an outsole to the bottom of the shoe, turning the upper out, progressively shaping the upper to the last and forcing the angle of the upper between the insole and the outsole, permanently securing the upper to the outsole in said angle as the shaping progresses, laying a welt upon the outturned margin of the upper and uniting the welt, upper and outsole.

7. That improvement in the art of making shoes which consists in assembling upon a last beveled along the bottom edge an insole and an upper and lining, turning the lining in and cementing it down upon the insole all the way around, turning the heel end of the upper in and lasting it down upon the heel end of the insole, placing upon the bottom of the shoe an outsole having at its heel end a raised welt abutting portion, turning out the upper through the shank and forepart, forcing the angle of the upper beneath the edge of the insole and beneath the overhanging beveled edge of the last, inserting staples in said angle of the upper through the upper into the outsole, laying a welt upon said outturned portion of the upper, and uniting the welt, upper and outsole with stitches.

8. That improvement in the art of making shoes which consists in assembling upon a last beveled along its bottom edge an insole and an upper and lining, turning in the lining and securing it to the insole, thus shaping the insole to the bottom of the last, placing an outsole upon the shoe, turning out the lower margin of the upper, progressively shaping the upper to the last and forcing the angle of the upper beneath the edge of the insole and under the overhanging beveled portion of the last, permanently securing the upper to the outsole, as the shaping progresses, by staples inserted in said angle through the upper into the outsole, placing a welt upon the outturned margin of the upper with the edge of the welt in the crease between the insole and outsole and uniting the welt, upper and outsole with stitches.

9. That improvement in the art of making shoes which consists in assembling upon a last beveled along the bottom edge an insole and an upper and lining, turning the lining in and securing it to the bottom of the insole, thus shaping the insole to the bottom of the last, applying an outsole, turning the upper out, progressively shaping the upper

to the last and forcing the angle of the upper between the insole and outsole beneath the beveled edge of the last, permanently securing said upper to the outsole in said angle as the shaping progresses, placing a welt upon the outturned margin of the upper and uniting the welt, upper and outsole.

10. That improvement in the art of making shoes which consists in assembling upon a last beveled along the bottom edge an insole and an upper, applying an outsole, turning the upper out and forcing the angle of the upper between the insole and outsole, securing the upper to the outsole in said angle, laying a welt upon the outturned margin of the upper and uniting the welt, upper and outsole.

11. That improvement in the art of making shoes which consists in assembling upon a last beveled along the bottom edge an insole and an upper and lining, turning the lining in and securing it to the bottom face of the insole, thus shaping the insole to the bottom of the last applying an outsole, turning the lower margin of the upper out, progressively shaping the upper to the last forcing the angle of the upper beneath the insole and the outsole beneath the beveled edge of the last, permanently securing the upper to the outsole, as the shaping progresses, by staples inserted in said angle, laying a welt upon the upper margin in such manner that the inner edge of the welt projects into said angle and covers the heads of the staples, and uniting the welt, upper and outsole.

12. That improvement in the art of making shoes which consists in providing an outsole at its heel end with a raised welt abutting portion, securing the welt to the upper and to the outsole, and abutting said welt at its two ends against the said abutting portion of the outsole.

13. That improvement in the art of making shoes which consists in attaching to the upper face of an outsole a welt abutting lift, securing the welt to the upper and to the outsole and abutting the ends of the welt against the exposed abutting edges of said lift.

14. That improvement in the art of making shoes which consists in assembling upon a last an upper and an insole, lasting the heel end of the upper in and turning the forepart of the upper out, providing upon the upper face of an outsole a raised abutting portion against which the ends of the outturned portion of the upper abut, attaching the outturned margin of the upper to said outsole, and attaching said outsole to the insole at its heel end.

15. That improvement in the art of making shoes which consists in assembling upon a last an insole and an upper and lining, turning in the lining and securing it to the insole all the way around, turning in the

heel end of the upper and lasting it down upon the insole, placing upon the shoe an outsole having upon the upper surface of its heel end a raised welt abutting portion, 5 turning out the upper through the shank and about the forepart, laying a welt upon said outturned portion of the upper, uniting the welt, upper and outsole with stitches and abutting the welt at both ends against 10 the raised abutting portion of the outsole.

16. That improvement in the art of making shoes which consists in assembling upon a last an upper and an insole over which the heel end of the upper may be lasted in, turning 15 in the heel end of the upper and lasting it down upon said insole, turning out the lower margin of the forepart, applying an outsole having secured to its upper face a raised welt abutting part extending, when 20 said outsole is located on the last, substantially to the forward edge of the lasted-in portion of the upper, laying a welt upon the outturned margin of the upper, uniting the welt, upper and outsole, and abutting the 25 ends of the welt against said abutting part.

17. That improvement in the art of making shoes which consists in assembling upon a last an upper and an insole which has its edge substantially flush with the bottom 30 edge of the last, turning in the heel end of the upper and lasting it down upon said insole, applying an outsole which has a margin projecting beyond the bottom edge of the last and which is provided upon the upper side of its heel end with a raised abutting portion extending substantially to the end of the turned-in portion of the upper, providing a space between the edge of the insole and the outsole, turning out the upper 35 through the shank and forepart, forcing the angle of the upper into said space between the insole and outsole, securing the upper to the outsole in said angle, laying a welt upon the outturned margin of the upper, abutting the ends of the welt against 40 said raised abutting portion of the outsole, and uniting the welt, upper and outsole.

18. That improvement in the art of making shoes which consists in assembling upon 45 a last an upper and lining and an insole, turning in the lining all the way around and securing it to the bottom face of the insole, lasting in the heel end of the upper upon the insole, securing to the upper face of an

outsole a lift having a margin of substantially the thickness of the upper and welt of the shoe, depressing that part of the lift which comes beneath the upper and the insole, applying said outsole to the last and cementing the outsole to the insole and lining, turning out the lower edge of the upper through the shank and about the forepart, laying a welt upon said outturned margin of the upper, uniting the welt, upper and outsole, and abutting the ends of the welt and the ends of the outturned margin of the upper against the exposed portion of said lift.

19. That improvement in the art of making shoes which consists in assembling upon a last an upper and an insole over which the heel end of the upper may be lasted in, turning in the heel end of the upper and lasting it down upon said insole, turning out the lower margin of the forepart, applying an outsole having secured to its upper face a raised welt abutting part, extending when said outsole is located on the last substantially to the forward edge of the lasted-in portion of the upper, laying a welt upon the outturned margin of the upper, uniting the welt, upper and outsole, abutting the ends of the welt against said abutting part, and uniting the outsole, the abutting part and the insole.

20. That improvement in the art of making shoes which consists in assembling upon a last an upper and an insole, applying an outsole which has a margin projecting beyond the edge of the insole and providing a space near the edge of the insole between the lower face of the insole and the upper face of the outsole, turning out the lower margin of the upper, progressively shaping the upper to the last and forcing the angle of the upper into the space between the insole and the outsole, permanently securing the upper to the outsole in said angle, as the shaping progresses, laying a welt upon the outturned margin of the upper, and uniting the welt, upper and outsole.

In testimony whereof I have signed my name to this specification in the presence of two subscribing witnesses.

ADAM H. PRENZEL.
